US0D1076458S

(12) **United States Design Patent** (10) Patent No.: **US D1,076,458 S**
(45) Date of Patent: ** May 27, 2025

(54) **PLASTIC FILM WITH SURFACE PATTERN FOR EMBOSSED**

(71) Applicant: **THE GLAD PRODUCTS COMPANY**, Oakland, CA (US)

(72) Inventors: **John Rusnak**, Willowbrook, IL (US); **Carl L Bergman**, Loveland, OH (US); **Mark D. Pszczołkowski**, Pleasanton, CA (US); **Daniel C. Peck**, Lebanon, OH (US); **Matthew W. Waldron**, West Chester, OH (US)

(73) Assignee: **THE GLAD PRODUCTS COMPANY**, Oakland, CA (US)

(**) Term: **15 Years**

(21) Appl. No.: **29/795,785**

(22) Filed: **Jun. 21, 2021**

Related U.S. Application Data

(62) Division of application No. 29/628,530, filed on Dec. 5, 2017, now Pat. No. Des. 925,926.
